Chinese Office Action dated Mar. 20, 2020, for Chinese Design Application No. 201930630649.5, a counterpart foreign application of the Design U.S. Appl. No. 29/693,023, 1 page.

Primary Examiner — Patricia A Palasik(74) *Attorney, Agent, or Firm* — Lee & Hayes, P.C.(57) **CLAIM**

The ornamental design for a mobile conveyer unit, as shown and described.

DESCRIPTION

FIG. 1 is a top, front, left-side perspective view of the mobile conveyer unit according to a present design;

FIG. 2 is a right-side view thereof;

FIG. 3 is a left-side view thereof;

FIG. 4 is a front view thereof;

FIG. 5 is a back view thereof;

FIG. 6 is a top view thereof; and,

FIG. 7 is a bottom view thereof.

The dashed broken lines depict portions of the mobile conveyer unit that form no part of the claimed design. The dot-dashed broken lines represent boundaries of the claimed mobile conveyer unit and form no part of the claimed design.

1 Claim, 7 Drawing Sheets(56)
